UNITED STATES PATENT OFFICE.

ARTHUR F. POOLE, OF KENILWORTH, ILLINOIS.

ELECTRIC CLOCK.

1,325,862.

Specification of Letters Patent. Patented Dec. 23, 1919.

Application filed June 11, 1917. Serial No. 174,058.

To all whom it may concern:

Be it known that I, ARTHUR F. POOLE, a citizen of the United States, residing at Kenilworth, in the county of Cook and 5 State of Illinois, have invented certain new and useful Improvements in Electric Clocks, of which the following is a specification.

My invention is a self-winding electric 10 clock, more particularly of the class of clocks employing conical pendulums as their regulating means.

One of the objects of my invention is to provide a self-winding clock of the above 15 described class which shall possess advantages over those of the prior art in the way of small consumption of current and simplicity of action.

Another object of my invention is to provide an efficient means of re-winding a clock 20 employing a conical pendulum and to design the re-winding means so as to insure the conical pendulum swinging in a circle.

A further object of my invention is the 25 provision of an electric actuating means for a conical pendulum, said means being adapted to give the pendulum two impulses at right angles to each other, whereby said pendulum is kept swinging in a true circular arc.

A still further object of my invention is the provision of the aforementioned actuating means for a conical pendulum with the addition of provisions for skipping or 35 missing an impulse in case the amplitude of vibration of the pendulum should exceed a predetermined arc.

The above and other objects of my invention will be apparent to those skilled in the 40 art from a perusal of the accompanying specification and claims.

My invention may be best understood by reference to the accompanying figures, of which—

45 Figure 1 is a plan view of my improved clock;

Fig. 2 is a section along the line 2—2 of Fig. 1;

Fig. 3 is a partial section along the line

50 3—3 of Fig. 1;

Fig. 4 is a detail taken along the section line 4—4 of Fig. 1;

Fig. 5 is a plan view of the electric actuating mechanism taken along the line 5—5

55 of Fig. 1;

Fig. 6 is a perspective view of the actu-

ating mechanism for the pendulum, said view including the electromagnets, a revolving armature and also the contact-making devices; and

Fig. 7 is a diagram showing the path of the pendulum bob in full line and the components of its path in dotted lines.

Similar numbers of reference refer to like parts throughout all the figures.

Referring particularly to Figs. 1 and 3, I have provided a base 10, which serves as a support for a tube or casing 11, which serves the double purpose of providing a casing for the battery 12 and a support for 70 the pendulum 13 and dial 17. Attached to the top of the casing 11 is a bar 14, from which at 15 is suspended the pendulum 13 by a fine wire or other equivalent supporting means 16. The bar 14 also serves as 75 a support for the dial 17 and gear mechanism used in connection therewith and hereinafter to be described. The pendulum 13 is of the kind known as a conical pendulum, that is, instead of vibrat- 80 ing to and fro in a plane, it swings in a circular arc. It is well known that a circular arc may be resolved into two simple harmonic vibrations of the same amplitude and period and displaced 90° in phase. Re- 85 ferring to Fig. 7, if the pendulum is given a simple harmonic vibration in the line 48—101 and also a simple harmonic motion in the line 84—102 at right angles to the former line, and these two motions were of 90° the same amplitude and period and 90° displaced in phase, the resultant path of the pendulum bob would be that of the full line circle 48—84—101—102. I, therefore, have provided an actuating mechanism to insure 95 that the motion of the pendulum 13 shall always be the result of two simple harmonic motions of equal amplitude and at right angles to each other and displaced 90° in phase.

The actuating mechanism for the pendulum consists of a revolving shaft 18, supported in suitable bearings 19, 20, attached to the framework 10. On this shaft is an armature 21 having four arms 22, 23, 24, 25, arranged 90° apart. An electromagnet 26, having recessed pole pieces 27, serves to attract either the arms 22, 23, or the arms 24, 25, when current is sent through said magnet.

The general plan of my actuating mechanism is to give the pendulum an impulse

when either of the plane components of the motion of the pendulum decreases below a certain arc. A further purpose is to delay such impulses until the pendulum has moved 5 through an arc of 90° from the point at which the giving of said impulse was determined. It is obvious that if one were to determine that an impulse should be given to the pendulum by the fact of the pendulum's 10 falling below a predetermined arc and would give that impulse at the time when said determination had been made, the component of the pendulum's motion at right angles to the component determining the giving of 15 an impulse would be increased. It is therefore necessary to delay the giving of the impulse until the pendulum has moved through an arc 90° from the point at which the giving of the impulse was determined. 20 I shall now describe the means by which the circuit is closed through the electric magnet 26 in order to give an impulse corresponding to the above recited conditions. The electromagnets 26 are in circuit with 25 the battery 12, which preferably consists of dry cells and is adapted to be contained in the casing 11. One pole of the battery is connected by the conductor 100 to the electromagnets 26 and the other pole of the 30 battery is connected by a conductor 27' to a wire 28, which in its turn is connected to the contact springs 29, 30, which are insulated from the framework of the machine. Neglecting for a moment the contact spring 35 30, since the function of this spring is largely a duplication of that of the spring 29, the other side of the electromagnet 26 is connected by the conductor 31 to a conductor 32, which is common to the lower contact 40 springs 33, 34. Obviously contact of the springs 29 and 33, or of the springs 30 and 34, will result in current flowing through the magnet 26 and attraction either of the armatures 22 and 23 or the armatures 24 and 45 25, according to the particular pair of contact springs which have been closed. The contact spring 29 is insulated from the arm 35, on which said spring is mounted, and said arm is pivoted on the framework of 50 the clock at 36 and has an upwardly extending arm 37 on which is mounted a roller 38. A spring 39 extends between the arm 35 and the framework of the machine and tends to hold the arm and the thereon mounted 55 spring 29 in contact with a stop pin 40 on the frame of the machine. The lower contact spring 33 is mounted on an arm 41, which is pivoted on the framework at 42 and is held by a spring 43 against a stop pin 60 44 mounted on the framework. The arm 41 has extending therefrom a finger 45, which is adapted to be engaged by a latch 46 pivoted on the framework at 47. The latch 46 is made of steel and the upper end 65 48 thereof is magnetized so as to form a per-

manent magnet. The magnet 48 is adapted to be actuated by a permanent magnet 49, which is on the lower end of the pendulum 13.

As the pendulum swings around, it is obvious that so long as it swings in an arc so that the magnet 49 travels over the magnet 48, the latch 46 will be dragged around by the action of the magnets 48 and 49, and will be thrown into its position, as shown 70 in Fig. 6. This tilting of the latch 46 determines that after the pendulum has been moved through an arc of 90° a short impulse will be given to it and it will be noted that this impulse is not given until the pendulum 75 has moved 90° from the position shown in Fig. 1. This delaying of the impulse determines that the impulse which is thus given to the pendulum will be in a direction to increase the motion of the pendulum in 80 the plane of the paper in Fig. 1. Referring to Fig. 7, when the pendulum passes 48 it is determined that an impulse shall be given, the impulse is delayed until the pendulum has reached the point 84, when a tangential 85 impulse is given. This will increase the component along the line 48—101.

The impulse of the electromagnet 26 is communicated to the pendulum by means of a crank arm 50, rigid with the shaft 18, 90 and having a fork 51 which embraces the pendulum rod 52. Rigid on the shaft 18 is a pin 53, which is adapted to contact with the roller 38 and thereby lower the arm 35 (Fig. 6). Rigidly mounted on the shaft 100 18 is a second pin 54, which serves to contact with a roller 55 mounted on the arm 41 and depress the rear end of said arm, consequently elevating the front end of said arm as the pin 54 passes over the roller 55. 105

The cycle of action of the contact-closing parts is as follows: The pin 54, by its contact with the roller 55, first elevates the finger 45 to a position to be caught by the latch 46. After this is accomplished, the magnet 110 49 passes over the magnet 48 and attracts the latch 46 in the direction of motion of the pendulum in case the arc is of an amplitude determining that an impulse shall be given. When the pin 54 passes out of 115 contact with the roller 55, the arm 41 is held in its elevated position, as shown in Fig. 6, by the engagement of the latch 46 with the finger 45. 90° after the pendulum has passed the latch 48 and pin 53 contacts 120 with the roller 38 and moves the same, thereby causing the spring 29 to be depressed, and a contact point 56 on said spring engages with a contact point 57 on the spring 33 and closes the circuit of the electromagnet 26. In this position the armatures 22 and 23 are attracted and the impulse is transmitted to the pendulum rod 52 by means of the crank arm 50. As soon as the pin 53 passes out of contact with the roller 125 130

38, the arm 35 returns to its normal position and opens the circuit. 90° after the circuit has been broken a pin 88 on the shaft 18 engages the roller 55 and depresses said 5 roller to a lower point than it was depressed by the pin 54. This serves to engage the finger 45 with a cam surface 59 on the latch 46 and restores said latch to its normal position, where it is held by a stop pin, not 10 shown. The latch 46 is arranged to be slightly off of the vertical when it is against said stop pin, so that if it has been thrown against said pin by the action of the finger 45 on the cam 59, it will remain in that 15 position until again dragged forward by the action of the magnet 49.

To sum up the action of the mechanism just described, just before the passage of the magnet 49 over the magnet 48, the pin 20 54 elevates the finger 45 into a position to be caught by said latch in case said latch should be dragged to its alternative position by the magnet 49 on the bottom of the pendulum 13. In case the arc of the pendulum 25 is such that the magnet 49 is in the field of the magnet 48, the latch 46 is thrown to the position shown in Fig. 6, after which the pin 54 passes over the roller 55. The arm 41 remains in its latched position ready 30 to close the circuit when the arm 35 shall be subsequently acted upon by the pin 53.

It will not be necessary to go into detail as to the description and action of the parts 35 60 to 68, since they differ only from the action of the contact-making devices under control of the latch 46 in that the action of these latter parts occur 90° after the action of the former parts.

It is, of course, to be noted that the action 40 of the pin 88 upon the roller 55 does not depress said roller far enough to bring the contact points 56, 57, into contact a second time, since at the time the pin 88 acts on the roller 55 the arm 35 is in its normal position, against the stop pin 40 and the two points 56, 57, do not come into engagement.

It is, of course, necessary to provide some 45 means for keeping count of the revolutions of the pendulum, and to this end I have 55 provided the shaft 18 with a bevel gear 69 engaging a bevel gear 70 on a horizontal shaft 71 mounted on the base 10. A bevel gear 72 on the shaft 71 engages a bevel 73 mounted on a vertical shaft 74, on the upper end of which is a worm 75, engaging a worm gear 76 mounted on a horizontal shaft 77 supported from the bar 14. On the front end of said shaft is a reducing gear 78, diagrammatically shown at 78, which is 55 60 the proper ratio to actuate the clock hands 79. These gears are diagrammatically shown, since the matter of designing a gear ratio to translate the period of motion of the pendulum 13 into proper motion of the 65 hands 79 is well within the province of those

skilled in the art. I have provided a regulating nut 81, which engages a screw thread upon the pendulum rod 52 and thereby serves as a means to regulate the period of vibration of the pendulum.

The entire clock movement is mounted on the upper part of the base plate 10, which also serves as a support for a glass shade 83, which covers the movement. It is to be noted that the position of the shaft 77, on 75 account of the worm gear 76, is such that it does not interfere with the movement of the pendulum 13.

My herein described apparatus has many advantages which will be apparent to those 80 skilled in the art, among which I may mention the entire absence of noise, owing to the fact of the conical pendulum being used and also to the fact that there being no sudden actions in which parts are accelerated and 85 then brought to a full stop. The armatures of the electromagnets 27 revolve past the poles of said magnets and the permanent magnet 49 never comes in contact with the permanent magnets 48 and the similar mag- 90 net 84 on the latch 60.

I believe I am the first to show means for applying an impulse to the two components of motion of a conical pendulum and for governing the amount or frequency of said 95 impulses by the amplitude of vibration of the pendulum itself. It is obvious that my herein described structure will maintain the two simple harmonic vibrations constituting the circular motion of the pendulum 13 100 100 at a constant amount since if the component 48—101 (Fig. 7) is exceeded the latch 48 will not be actuated and consequently when the pin 54 passes from engagement with the roller 55 the arm 41 will be returned by the spring 43 to its normal position and no impulse will be given upon the subsequent engagement of the pin 53 with the roller 58.

By the same reasoning, the component 110 84—102 will be maintained constant by the actuation or non-actuation of the magnet 84, and obviously, if the two components of the circular motion are maintained at a constant magnitude, the motion of the pendulum 13 must approximate to that of a true circle.

As before noted, I have provided a casing 11 to contain the battery 12, which is preferably in the form of a plurality of cells 120 mounted in a single tube or unit. Batteries of this kind are commonly used in connection with electric flashlights. The battery connections are simple, as will be plain from a reference to Fig. 1. One pole of the battery contacts with a conducting pin 90, mounted in an insulator 93 and held in its position by a spring 91, which in its turn is held to the insulating block 93 by a screw 92. It will be understood that the spring 91 is 130

thereby insulated from the framework. The conductor 27 is attached to the spring 91 by a screw 94.

The connections to the top pole 95 of the battery 12 are made by means of a contact plate 96, which turns about a screw 97 as a hinge and is held in contact with the pole 95 by a spring 98 also mounted on the screw 97. The conductor 100 is attached to the hinge 96 by a screw 99. It is to be understood that both the conducting plates 91 and 96 are insulated from the framework of the machine and that an insulating washer (not shown) is provided in the bottom of the tube or casing 11 to prevent the battery 12 from coming into electrical contact with the framework of the clock.

Of course, it is possible to ground one pole of the battery on the framework and use the framework itself as a part of the electric circuit. However, I prefer to keep the framework entirely insulated from the circuit, since I consider this construction more reliable.

I have shown the pendulum kept in its circular motion by maintaining two arcs of vibration in planes at right angles to each other. However, it is by no means necessary that my herein described invention be confined to the right-angled arrangement. It is obvious that there might be provided three sets of contact devices like those associated with the magnet 48, these three sets being placed at an angle of 120° with respect to each other. Maintaining the three components of the pendulum's motion equal would, of course, cause the pendulum to describe a circular arc. Other arrangements might be used, since two or more harmonic motions of equal amplitude and period can be combined in a vast number of ways to give a resultant of circular motion.

Many changes and modifications may be made in my herein described structure without departing from the spirit of my invention, since I claim:

1. In a clock, the combination of a conical pendulum, means to give an impulse to said pendulum, means to ascertain the vibration of said pendulum in one plane and give or withhold the impulse from said pendulum according to said vibration, and other means for automatically determining by the amplitude of its vibration in a second plane whether a second impulse shall be given to the pendulum.

2. In a clock, the combination of a conical pendulum, means to give said pendulum an impulse, means controlled by the amplitude of vibration of the pendulum in one plane to determine whether or not an impulse shall be given, and other means controlled by the amplitude of vibration in a second plane to determine whether an impulse shall be given.

3. In a clock, the combination of a conical pendulum, means to give said pendulum an impulse, means controlled by the amplitude of vibration of the pendulum in one plane to determine whether or not an impulse shall be given, and electric means controlled by the amplitude of vibration in a second plane to determine whether the impulse should be given.

4. In a clock, the combination of a conical pendulum, means to give said pendulum an impulse, means controlled by the amplitude of vibration of the pendulum in one plane to determine whether or not an impulse shall be given, and electric means controlled by the amplitude of vibration in a second plane at right angles to said first plane to determine whether an impulse shall be given.

5. In a clock, a conical pendulum, means for giving the pendulum an impulse, and means governed by the motion of said pendulum for determining when an impulse shall be given.

6. In a clock, the combination of a conical pendulum, electromagnetic means for giving said pendulum an impulse, and means including a permanent magnet governing the action of said magnet for determining when an impulse should be given.

7. In a clock, the combination of a pendulum swinging through an arc, means to give said pendulum an impulse, and means including a permanent magnet and governed by the amplitude of vibration of the pendulum to determine whether or not said impulse giving means shall be called into action.

8. In a clock, the combination of a pendulum, electromagnetic means adapted to give an impulse to said pendulum, magnetic means whose action is determined by the amplitude of the vibration of said pendulum for determining whether or not said impulse shall be given.

9. In a clock, the combination of a pendulum, electromagnetic means for giving an impulse thereto, circuit making devices included in the circuit of said electromagnetic means, and magnetic means whose action is governed by the vibration of the pendulum to determine the action or non-action of the circuit making devices.

10. In a clock, the combination of a pendulum, electromagnetic means for giving an impulse thereto, circuit closing devices associated with said electromagnetic means, magnetic determining means whose action is determined by the amplitude of vibration of the pendulum for determining the action or non-action of said circuit closing means.

11. In a clock, the combination of a conical pendulum, a magnet having a normal and a displaced position arranged in proximity to the path of said pendulum, and

means associated with the pendulum to displace said magnet from a normal position.

12. In a clock, the combination of a conical pendulum, a latch having a magnet on one end thereof located adjacent to the path of the pendulum, said latch being adapted to keep a displaced and a normal position, and means moving with said pendulum for moving said latch from its normal and its displaced position.

13. In a clock, the combination of a conical pendulum, a latch having a permanent magnet on one end thereof located adjacent to the path of the pendulum, said latch being adapted to keep a displaced and a normal position, and means moving with said pendulum for moving said latch from its normal and its displaced position.

14. In a clock, the combination of a conical pendulum, a latch having a magnet on one end thereof located adjacent to the path of the pendulum, said latch being adapted to keep a displaced and a normal position, and means moving with said pendulum for moving said latch from its normal and its displaced position when the arc of the pendulum reaches a certain predetermined limit.

15. In a clock, the combination of a conical pendulum, a pivoted latch adapted to occupy a normal and a displaced position, said latch having magnetic means mounted on the free end thereof, electromagnetic means adapted to give an impulse to said pendulum, circuit closing devices controlling the action of said electro-magnetic means, and a shaft rotating synchronously with the pendulum and adapted to operate said circuit closing devices.

16. In a clock, the combination of a conical pendulum, a pivoted latch adapted to occupy a normal and a displaced position, said latch having magnetic means mounted on the free end thereof, electromagnetic means adapted to give an impulse to said pendulum, circuit closing devices controlling the action of said electromagnetic means, and a member moving synchronously with the pendulum and adapted to operate said circuit closing devices.

17. In a clock, the combination of a conical pendulum, electromagnetic means to give an impulse thereto, circuit closing devices adapted to govern the action of said electromagnetic means, a second set of circuit closing devices also adapted to govern the action of said electromagnetic means and means connecting said circuit-closing devices and electromagnetic means, whereby either set of circuit-closing devices is adapted to deter-

mine that an impulse shall be given to said pendulum.

18. In a clock, the combination of a conical pendulum, electromagnetic means to give an impulse thereto, circuit closing devices 65 adapted to govern the action of said electromagnetic means, and a second set of circuit closing devices also adapted to govern the action of said electromagnetic means, said circuit closing devices being adapted to be 70 brought into action by the pendulum one after the other.

19. In a clock, the combination of a conical pendulum, electromagnetic means to give an impulse thereto, circuit closing devices 75 adapted to govern the action of said electromagnetic means, and a second set of circuit closing devices also adapted to govern the action of said electromagnetic means, one of said circuit closing devices being 80 adapted to be brought into action by said pendulum at one point of its travel and the other of said circuit closing devices being adapted to be brought into action by said pendulum when it is in a plane at right 85 angles to said first point.

20. In a clock, the combination of a conical pendulum swinging through an arc, means to give said pendulum an impulse, and means governed by the amplitude of 90 vibration of the pendulum to determine whether or not said impulse giving means shall be called into action.

21. In a clock, the combination of a conical pendulum, electromagnetic means adapted to give an impulse to said pendulum, magnetic means whose action is determined by the amplitude of the vibration of said pendulum for determining whether or not said impulse shall be given.

22. In a clock, the combination of a conical pendulum, electromagnetic means for giving an impulse thereto, circuit making devices included in the circuit of said electromagnetic means, and magnetic means 105 whose action is governed by the vibration of the pendulum to determine the action or non-action of the circuit making devices.

23. In a clock, the combination of a conical pendulum, electromagnetic means for 110 giving an impulse thereto, circuit closing devices associated with said electromagnetic means, magnetic determining means whose action is determined by the amplitude of vibration of the pendulum for determining the 115 action or non-action of said circuit closing means.

Signed at Chicago, Illinois, this 7th day of June, 1917.

ARTHUR F. POOLE.
